INVENTOR

BY *Victor J. Evans*
ATTORNEY

UNITED STATES PATENT OFFICE.

DELBERT L. SCHUSTER, OF PLATTEVILLE, WISCONSIN.

BULL RING.

1,413,434.

Specification of Letters Patent. Patented Apr. 18, 1922.

Application filed May 27, 1921. Serial No. 473,214.

To all whom it may concern:

Be it known that I, DELBERT L. SCHUSTER, a citizen of the United States, residing at Platteville, in the county of Grant and State 5 of Wisconsin, have invented new and useful Improvements in Bull Rings, of which the following is a specification.

This invention relates to a bull ring and has for its primary object the construction 10 of a ring that is self locking and which is of a construction that the same may be readily forced through the nose of an animal.

An object of the invention is the novel manner of shaping the point and associating 15 the same with the catch so that the end of the ring when in an open position will be readily inserted through the nose of the animal and then immediately lock and when in a locked position cannot be accidentally 20 disconnected.

With these and other objects in view the invention will be better understood from the following detailed description taken in connection with the accompanying drawing 25 wherein:

Fig. 1 is a side elevation of the ring.

Fig. 2 is an enlarged sectional view of the locking connection.

Again referring to the drawing illustrating one of the many constructions of my invention the numerals 1 and 2 designates a pair of companion members pivotally connected as indicated at 3 so that the ends 4 and 5 may swing towards and away from 35 each other. The end 4 is provided with a penetrating point 6 adapted to be received within the recess 7 in the end 5. It will be noted that the penetrating point is of a shape to have a cam surface 8 co-operating 40 with a cam surface 9 on a catch 10 which retracts the same in the inserting of the point within the recess so that the catch can automatically snap into the notch 11 in the point through the action of the spring 12.

To complete my invention I provide a pin 45 13 projecting through slots 14 in the wall of the member 2 so that the finger nail may be used to retract the catch from the point when the ring is to be opened.

From the foregoing description taken in 50 connection with the accompanying drawing it will be apparent that I provide a ring that may be readily forced through the nose of an animal and which is self locking and in which the parts are so constructed and 55 associated that the ring cannot be accidentally opened, but may be readily opened by a person when operated in the proper manner.

It is, of course, to be understood that the 60 invention may be constructed in various other manners and the parts associated in different relations, and, therefore, I do not desire to be limited in any manner except as set forth in the claims hereunto appended. 65

Having thus described my invention what I claim is:

1. A bull ring comprising a pair of pivoted connected members, a penetrating point on the end of one member adapted to be received within the recess in the other member, a spring operated catch within the recess to automatically snap into engagement with said point in the swinging movement of the members, and a pin projecting from 75 the catch through the wall of the member so the catch can be retracted.

2. A bull ring comprising a pair of circular members having certain ends pivotally connected together, a tapering point formed 80 on the remaining end of one member and having a cam surface, a recess formed in the remaining end of the other member for receiving the point, a spring pressed catch pivotally mounted in the recess and having a 85 cam surface cooperating with said first cam surface to retract the catch in the insertion of the point into the recess, said point being further provided with a notch for engaging the catch when the point has been fully 90 forced into the recess, and a pin passed through the catch and mounted in slots in one of the members for retracting the catch.

In testimony whereof I affix my signature.

DELBERT L. SCHUSTER.
